UNITED STATES PATENT OFFICE.

FRED WEGNER, OF FAIRPORT, NEW YORK.

CAN-HEADING MACHINE.

1,095,972.

Specification of Letters Patent.

Patented May 5, 1914.

Application filed October 18, 1907. Serial No. 398,006.

To all whom it may concern:

Be it known that I, FRED WEGNER, of Fairport, in the county of Monroe and State of New York, have invented certain new and useful Improvements in Can-Heading Machines; and I do hereby declare the following to be a full, clear, and exact description of the same, reference being had to the accompanying drawings, forming a part of the specification, and to the reference-numerals marked thereon.

The present invention which relates to can heading machines has for an object to provide an improved construction in which filled cans in upright positions are fed to a can heading mechanism without injury to the cans or without the spilling of the contents of the latter.

Another object is to provide for properly positioning the tops on the cans before the latter reach the can heading mechanism.

To these and other ends the invention consists in certain improvements and combinations of parts all as will be hereinafter more fully described, the novel features being pointed out in the claims at the end of the specification.

In the drawings: Figure 1 represents a side view of a machine constructed in accordance with this invention. Figs. 2, 3, 4 and 5 represent sections respectively on lines *a—a*, *b—b*, *c—c* and *d—d* of Fig. 1. Fig. 6 represents a view of the other side of the machine, parts being shown removed for the purpose of clearness. Figs. 7 and 8 represent two views of the feeding mechanism showing the latter in full lines in two positions, and in dotted lines in another position, and Fig. 9 represents a detail view of the ejector.

In the present embodiment of my invention, there is employed a frame or upright A upon which is suitably supported a can rotating member 1 and a rotary can support 2. These parts may be mounted in any suitable manner, but it is preferred to secure the former on the lower end of a vertical shaft 4 which carries a pulley 5 driven by a belt 6 passing over idlers 7 and around a pulley 8 on drive shaft 9. The can support is arranged below and in axial alignment with the can rotating member and is preferably movable toward the can rotating member in order that a can may be clamped between

these parts, being for this purpose journaled on the upper end of a carrier 10 which is movable vertically in brackets 11 projecting from the front face of the frame A.

The mechanism for moving the rotary can support toward the can rotating member comprises a horizontally arranged shaft 12 journaled in a bracket 13 and positioned on the front of the frame A below the carrier 10. Arranged on this shaft is a cam 14 on which rides a roller 15 on the carrier in order that the latter may rise and fall under the action of the cam. The roller 15 may be yieldingly supported on the carrier so that the can may be held with yielding pressure. In the present instance, this yielding support is in the form of a socket piece 16 slidably on the lower end of the carrier and connected by links 17 with a collar 18 loosely surrounding said carrier. This collar is loosely connected to a ring 19 by bolts 20 which are surrounded by rubber cushions 21 arranged between the collar and the ring.

Arranged to act on a can clamped between the can support and the can rotating member is a seaming mechanism which in this instance comprises a pair of seaming rollers 22 carried by the slides 23 which are moved to seaming positions by cam bars 24 in turn operated by cams 25 on a horizontal shaft 26 arranged on the rear of the frame A. This cam shaft is operated by a worm 27 driven from a pulley 28 on drive shaft 9 and gearing with a worm wheel 29 on the cam shaft 26. A suitable driving connection between the cam shaft 26 and the cam shaft 12 is provided so that the latter may be continuously operated, and preferably comprises a shaft 30 journaled in brackets 31 on the side of the frame A and geared to both of said shafts by bevel pinions 32.

The cans are directed to the can support by a can guide 33 which is rigidly supported on the frame and has its outer end flared at 34 and its inner end located in proximity to and in a plane with the rotary can support when the latter is in a depressed position. The cans are fed by hand to the flared end and are caught by a suitable feeding mechanism and delivered to the can support. The feeding mechanism preferably comprises two cooperating feeding devices, one arranged on each side of the feeder and adapted to reciprocate in the direction of the

length of the guide, and also to move toward and from cans on the support. These devices, in this embodiment, are in the form of reciprocating and oscillatory bars 35 arranged on opposite sides of the guide and guided in bearings 36 on the latter. Can engaging devices 37 preferably project upwardly from the bars and have their upper ends overhanging the guide and formed with curved recesses to fit the walls of the cans, the ones first receiving the cans being elongated so that in event the can is not in proper position to be engaged by the feeding devices the can will not be crushed.

- 15 The reciprocation of the feeding devices is effected through the medium of the constantly operated cam shaft 12 by means of a crank disk 39 connected by a link 40 with the lower end of an arm 41 extending from 20 rock shaft 42 on frame A. This rock shaft 42 has an arm 43 projecting upwardly therefrom and connected by a link 44 with a head 45 which connects the bars 35 and permits the turning of the latter, but causes 25 them to reciprocate therewith. The oscillation of the feeding devices is effected by a pair of guides 46 and 47 connected at one end by a fixed switch 48 and at the other end by a movable switch 49, the movable 30 switch being normally held in one position by a spring 50. With these guides co-operates the lower end of an arm 51 which depends from one of the bars 35 and has a normal tendency, due to its weight, to travel 35 on the guide 46, this tendency being limited by a stop 52. However, when the arm passes the switch 49 the latter moves back into its path and causes it to travel on guide 47 until the end of the latter is reached, 40 when the arm again takes to guide 46. As the bars 35 are connected by a suitable device which transmits the motion of one to the other in a reverse direction the cans are gripped at the beginning of the forward 45 movement and released at the end of said forward movement. The device for effecting the simultaneous oscillation of the bars is preferably in the form of a link connecting two arms 53 projecting toward each 50 other, from the bars or shafts, one being directed downwardly, the other being directed upwardly, both being preferably turnable on the bars in order that the clamping action may be varied.
- 55 Owing to the shape of the walls of the recesses in the can engaging devices, the cans are compressed into circular shape when clamped thus permitting the can tops to drop into the bodies. Should, however, 60 the tops not be positioned properly they are shifted by suitable top positioning devices which are carried by the feeding devices and are preferably in the form of fingers 55 projecting upwardly therefrom.
- 65 While the cans are traveling on the guide

it is desirable to have them pass under a pressure device which prevents their relation to each other being disturbed, and at the same time holds their tops in place. This device preferably comprises a plate 56 extending longitudinally of the guide and having a spring pressed bearing piece 57 arranged longitudinally thereof, the outer ends 58 and 59 of the plate and the bearing piece 70 being deflected upwardly to permit the cans 75 to pass freely beneath the pressure device.

After the seaming of the can head or top, the cans may be removed from between the can support and the can rotating member by means of an automatically operating ejector 80 which preferably is in the form of a trip lever 60 pivoted intermediately of its ends at 61 in proximity to said parts, as by being mounted to turn on one of the bars 35, and being held against movement with the bar by means of an arm 62 which enters a groove 63 in one of the bearings 36. The lower end of this trip lever carries a dog 64, which is pressed downwardly by a spring 65 and is adapted to be engaged by a tappet 66 on the carrier 10 to operate the trip lever when the carrier descends, in order that the trip lever may eject the can on the can support. When the support rises the dog 64 yields and permits the tappet to pass it without operating the ejector.

Generally stated the operation is as follows: Cans are fed by hand or otherwise to the guide 33 so that they may be engaged by the walls of the first pair of recesses in 100 the feeding devices. At this point, or in advance thereof, caps or heads are placed on the cans and they are then carried toward the seaming mechanism and under the pressure device in a step by step or intermittent 105 manner by the feeding mechanism, the latter shaping the can and positioning the cover so that the latter will be forced into the body by the pressure device. As the can leaves the guide it goes to the can support 110 which then rises and clamps the can against the can rotating member. The can is now released by the feeding mechanism and the seaming mechanism operates on the can. During the seaming operation, the cam 14 115 maintains the can elevated, and the feeding devices move to take a new can. At the end of the seaming the can support drops and the ejector throws the can into the trough 67 and a new can is fed to the support.

A can heading machine constructed in accordance with this invention will seam cans at a very great speed without crushing them or spilling their contents, and further, cans 125 which have become distorted are shaped so that the tops will properly fit them. The construction is such that it is inexpensive to manufacture and at the same time simple in operation and durable in use.

I claim as my invention:

1. The combination with a can rotating member, means for rotating it, and a rotary can support, of a seaming mechanism, a cam shaft for operating the seaming mechanism, a vertically movable and non-rotatable carrier on which the can support rotates, a shaft carrying a cam to engage the vertically movable carrier and a shaft connecting both cam shafts. 5
2. The combination with a can rotating member, means for rotating it, and a rotary can support, of a seaming mechanism, a horizontal shaft to drive the seaming mechanism, a vertically movable and non-rotatable carrier on which the can supporting member rotates, a horizontal shaft arranged below said vertically movable carrier and having a cam to engage the latter, 15 and driving connection between the horizontal shafts. 20
3. The combination with an upright, a can rotating member, means for rotating it, a rotary can support, of a seaming mechanism, a horizontal cam shaft arranged on the rear of the upright for moving the seaming mechanism, a vertically movable and non-rotatable carrier on the front of the upright, carrying the rotary can support, a 25 horizontal shaft arranged below the vertically movable carrier and carrying a cam to engage the latter to elevate the can support, and driving connection between the horizontal cam shafts. 30
4. The combination with a can rotating member, means for rotating it, and a rotary can support, of a vertically movable and non-rotatable carrier on which the can support is mounted, a shaft having a cam 35 thereon to engage the vertically movable carrier, a reciprocating feeder, driving connection between the feeder and cam shaft, and means for effecting the oscillation of the feeder. 40
5. The combination with a guide for directing the cans, of a pair of can feeding devices for carrying the cans along the guide, arranged on opposite sides of the latter and mounted to reciprocate longitudinally thereof and also to swing to and from the cans thereon about axes located beyond the edges of the can engaging portions. 45
6. The combination of a can guide for directing the cans, of a pair of can feeding devices mounted on opposite sides of the guides and movable longitudinally thereof, and also toward and from the cans thereon on axes parallel with the can guide and below the can engaging portions. 55
7. The combination with a can rotating member and a rotary can support, of a can guide having the can support located at one end thereof, mechanism for moving the can support toward the can rotating member, and a pair of coöperating can feeding de- 60

- vices movable longitudinally of the guide to a point beyond the same to carry the cans to the can support and also movable toward and from the cans on the support to engage and to release said cans.
8. The combination with a can guide and a reciprocating feeding device for moving cans on the guide, of means for oscillating the latter embodying a pair of guides, a device connected to the feeding devices and traveling on the guides, and means for directing said traveling devices from one guide to the other.
9. The combination with a can guide and a reciprocating feeding device for moving the cans on the guide, of means for oscillating said device embodying a pair of guides, devices connected to the feeding devices and traveling on the guides, and means for directing the traveling devices from one guide to the other, embodying a fixed and a movable switch at opposite ends of the guides.
10. The combination with a can guide and a reciprocating feeding device for moving the cans on the guide, of means for oscillating said device, embodying an arm thereon, a pair of guides on which the arm travels and means for directing the arm from one guide to the other.
11. The combination with a can heading mechanism, of a reciprocating feeding device for carrying the cans to said heading mechanism, and means for oscillating said device embodying an arm on the feeding device, a pair of guides on which the arm travels, a fixed switch connecting the guides at one end, and a movable switch connecting the guides at the other ends.
12. The combination with a guide and a pair of reciprocating feeding devices mounted on opposite sides of the guide, of means for moving said feeding devices toward and from each other comprising an arm carried by one of said devices, a pair of guides on which the arm travels, means for directing the arm from one guide to the other, and means connecting said reciprocating feeding devices for effecting their simultaneous movement.
13. The combination with a can guide, and a pair of reciprocating and oscillatory bars, can engaging devices projecting upwardly from the bars, an arm extending downwardly from one of the bars, a pair of guides on which the arm travels, means directing the arm from one guide to the other, and connection between the bars for causing their simultaneous oscillation in opposite directions.
14. The combination with a can heading mechanism, of a guide for directing cans thereto, a pair of reciprocating and oscillatory bars, can engaging devices carried by the bars, and connection between the bars to cause the can engaging devices on the two

- bars to move simultaneously toward and from each other, comprising two arms each carried by a bar and projecting toward the other, and a link connecting said arms.
5. 15. The combination with a can heading mechanism, of a guide for directing cans thereto, a pair of reciprocatory and oscillatory bars, can engaging devices carried by the bars, and connection between the bars to cause the can engaging devices on the two bars to move simultaneously toward and from each other, comprising two arms each rotatably adjustable on one of the bars and projecting toward the other and a link connecting said arms.
10. 16. The combination with a can heading mechanism, of a guide for directing cans thereto and a feeding mechanism comprising a pair of reciprocatory and oscillatory bars one on each side of the guide and can engaging devices projecting vertically from the bars.
15. 17. The combination with a guide for directing the cans, of a feeding mechanism comprising a pair of reciprocatory and oscillatory bars, one on each side of the guide, and can engaging devices projecting upwardly from the bars and having a plurality of curved recesses.
20. 18. The combination with a can heading mechanism, of a guide for directing cans thereto, and a feeding mechanism comprising a pair of coöperating can engaging devices mounted to reciprocate and also to move to and from cans on the guide, and having a plurality of curved recesses, the one first receiving a can being elongated to freely engage the same.
25. 19. The combination with a can heading mechanism, of a feeding mechanism for moving the cans to the can heading mechanism, and means acting upon the can heads or covers while the cans are on the feeding mechanism and before the cans reach the can heading mechanism to position or center said heads on the cans.
30. 20. The combination with a can heading mechanism, of a guide for directing cans thereto, a feeding mechanism comprising a pair of devices engaging opposite sides of the cans on the guide and mounted to reciprocate and also to move to and from the cans on the guide, and top positioning devices carried by the can engaging devices.
35. 21. The combination with a guide for directing the cans, of a reciprocatory device for moving the cans on the guide, carrying a top positioning device and movable toward and from cans on the guide.
40. 22. The combination with a can heading mechanism, of a guide for directing cans thereto, and a reciprocatory feeding device for moving the cans carrying a top positioning device and movable toward and from cans on the guide.
45. 23. The combination with a can heading mechanism, of a guide for directing cans thereto, and a feeding mechanism comprising a pair of devices engaging opposite sides of the cans on the guide and mounted to reciprocate and also to move to and from the cans on the guide, and top positioning devices carried by the can engaging devices.
50. 24. The combination with a can heading mechanism, of a guide for directing cans thereto, a pair of reciprocatory and oscillatory bars, one arranged on each side of the guide, means for reciprocating said bars, an arm depending from one of said bars, a pair of guides on which the arm travels, switches at the ends of the guides, upwardly projecting can engaging devices carried by the bars, and connection between the bars.
55. 25. The combination with a can rotating member and a rotary can support, of a movable carrier for the can support, an ejector pivoted intermediately of its ends on the axis transverse to the line of movement of the carrier and having its upper end movable to engage a can on the support, a tappet on the carrier and a spring pressed dog on the lower end of the ejector adapted to cooperate with the tappet to operate the ejector when the carrier moves away from the can rotating member and to permit the tappet to pass it when the carrier moves toward the can rotating member.
60. 26. The combination with a rotary can support and a can rotating member, one of which is movable toward the other, of a guide directing the cans to the can support, an intermittently acting feeding device for moving the cans on the guide, a device acting on the cans before they reach the said support to insert the heads in the cans, and a seaming mechanism for operating on a can arranged between the support and the can rotating member.
65. 27. The combination with a can rotating member and a rotary can support arranged below and movable toward the same, of a feeding device for moving the cans to the can support, a vertically movable carrier on which the can support is mounted, a continuously operable shaft having a cam thereon coöperating with the carrier, and connection between said cam shaft and the feeding device for operating the latter to move the cans to the can support.
70. 28. The combination with a guide for directing the cans, of a can feeding device for carrying the cans along the guide arranged on one side of the latter and adapted to reciprocate longitudinally thereof and also to swing to and from the cans thereon about an axis located beyond the edges of the can engaging portion.
75. 29. The combination with a can guide and a reciprocating feeding device for the cans
80. 85. 90. 95. 100. 105. 110. 115. 120. 125. 130.

on the guide having a can engaging portion, of means for moving the can engaging portion toward and from the cans on the guide embodying an arm movable with the can 5 engaging portion, a pair of guides on which the arm travels, and means for directing the arm from one guide to the other.

30. The combination with a guide for supporting the cans, of a feeding mechanism comprising a reciprocatory device movable longitudinally of the guide, and a can engaging member movable on and with the reciprocatory member to move a can on the guide, and mechanism for causing said 10 can engaging member to move toward the can at one end of the reciprocating movement and away from the can at the other end of the reciprocating movement, said mechanism having provision whereby the 15 can engaging member is held away from can engaging operation during the greater portion of the return movement.

31. The combination with a can guide, of feeding mechanism comprising a reciprocatory member operating beneath the guide, and can engaging members movable with the reciprocating member and projecting upwardly from the latter on opposite sides of the guide, said can engaging members 25 being also movable toward and from the cans on the guide to engage the cans at points above the guide.

32. In a can heading machine for seaming covers on cans, the combination with a seaming mechanism, of a can support and an opposing member between which and said support the can body and cover are clamped and held during the seaming operation, can positioning jaws engaging the periphery of 35 the can body, and can cover positioning means engaging the periphery of the cover, said can positioning jaws and cover positioning means holding the cover and can body centered in respect to each other until 40 clamped between said support and said opposing member, and said opposing member holding the cover seated in the can body until seamed thereto by said seaming mechanism; substantially as specified.

50. 33. In a can heading machine for seaming covers on cans, the combination with a seaming mechanism, of a can support and an opposing member between which and said support the can body and cover are clamped 55 and held during the seaming operation, can positioning jaws engaging the periphery of the can body, and can cover positioning means engaging the periphery of the cover, said can positioning jaws and cover positioning means holding the cover and can body centered in respect to each other until 60 clamped between said support and said opposing member, and said opposing member holding the cover seated in the can body until seamed thereto by said seaming mechanism; substantially as specified.

65. 34. In a can heading machine for seaming covers on cans, the combination with a 70 seaming mechanism, of a can support and an opposing member between which and said support the can body and cover are clamped and held during the seaming operation, can positioning jaws engaging the periphery of the can body, and can cover positioning means engaging the periphery of the cover, said can positioning jaws and cover positioning means holding the cover and can body centered in respect to each other until 75 clamped between said support and said opposing member and said opposing member holding the cover seated in the can body until seamed thereto by said seaming mechanism, said can body positioning jaws having curved recesses conforming to the periphery of the can body to true the same up, substantially as specified.

80. 35. In a can heading machine for seaming covers on can bodies, the combination with a seaming mechanism, of a can support and an opposing member between which and said support the can body and cover are clamped, means peripherally engaging the can body and cover for truing up the can body and centering the cover therewith until clamped by and between said support and opposing member, said support and opposing member holding the cover seated in the can body until seamed thereto by said seaming mechanism, 85 said can body positioning jaws having curved recesses conforming to the periphery of the can body to true the same up, substantially as specified.

90. 36. The combination with a can seaming mechanism, of a can support and opposing member for clamping the can body and cover together during the seaming operation, and can body truing and can cover centering means peripherally engaging the can body and can cover and holding the same centered in respect to each other until clamped between said support and opposing member, said support and opposing member holding the cover seated in the can body until seamed thereto, substantially as specified.

105. 37. In a can heading machine, the combination with the seaming mechanism, of means for successively delivering the assembled can parts thereto, which means comprise a reciprocating carriage having jaws which close to embrace a can body prior to reciprocation of said carriage and open to release said body after the latter has been advanced by said carriage, means for retaining the can parts in proper assembled condition during transit and prior to the seaming operation, and actuating mechanism initially operable to open or close said jaws and further operable to advance or retract said carriage.

115. 38. In a can heading machine, the combination, with the seaming mechanism, of 120

means for successively delivering the assembled can parts thereto, which means comprise a reciprocating carriage having jaws which close and embrace a plurality of can bodies prior to reciprocation of said carriage and open to release said bodies after the latter have been advanced by said carriage, means for retaining the can parts in proper assembled condition during transit and prior to the seaming operation, and actuating mechanism initially operable to open or close said jaws and further operable to advance or retract said carriage.

39. The combination with a guide for supporting containers, of a feeding mechanism comprising a reciprocatory device movable longitudinally of the guide, and a con-

tainer engaging member movable on and with the reciprocatory member to move a container on the guide, and mechanism for causing said container engaging member to move toward the container at one end of the reciprocating movement and away from the container at the other end of the reciprocating movement, said mechanism having provision whereby the container engaging member is held away from container engaging operation during the greater portion of the return movement.
